UNITED STATES PATENT OFFICE.

WILLIAM LISTER, OF CHICAGO, ILLINOIS.

RENDERING TANK.

Application filed July 1, 1918, Serial No. 242,768. Renewed February 6, 1922. Serial No. 534,591.

To all whom it may concern:

Be it known that I, WILLIAM LISTER, a citizen of the United States, and a resident of Chicago, in the county of Cook and State 5 of Illinois, have invented certain new and useful Improvements in Rendering Tanks, of which the following is a full, clear, and exact specification.

My invention is concerned with rotary 10 rendering tanks of the general character shown in the application of Lister No. 173,734, filed June 9, 1917, and is designed to provide such a tank with a steam jacket and various other improvements so that it 15 can be used more economically and expeditiously in carrying out the various rendering processes for which such tanks are employed.

To illustrate my invention, I annex here- 20 to five sheets of drawings in which the same reference characters are used to designate identical parts in all the figures of which—

Fig. 1 is a side elevation of a tank employing my improvements with the connecting 25 pipes associated therewith illustrated somewhat diagrammatically;

Fig. 2 is an end elevation with parts 30 broken away and as seen from the left-hand end of Fig. 1, and as showing the driving gearing which is omitted in Fig. 1;

Fig. 3 is a central longitudinal vertical section;

Fig. 4 is an enlarged view of the pipe connections seen at the left-hand end of Fig. 3 35 but on a larger scale;

Fig. 5 is a similar view of the connections seen at the right-hand end of Fig. 3; and

Fig. 6 is a detail of the elements associated with Fig. 4 but on a somewhat smaller 40 scale.

As a support for the tank in its preferred form, I employ the three columns 10 on one side, each of which is surmounted by the bearing bracket 11 for the grooved anti-friction roller 12 journaled therein, which 45 rollers co-operate with the three supporting rings 13 which are secured to the periphery of the tank in the manner which will be described. At the other side of the apparatus, I employ the two smaller base elements 14 which have secured thereon the bearing brackets 15 for a shaft 16, which shaft 16 has secured thereon the three grooved supporting and driving rolls 17. In line with 50 55 the base elements 14 is the larger base ele-

ment 18 which has secured thereon the bearing brackets 19 in which one end of the shaft 16 is journaled, which brackets have the bearings for the shaft 16, and between which bearings said shaft has secured thereon the 60 third of the driving and supporting rolls 17. A transverse horizontal drive shaft 21 journaled in the bearings 22 secured on top of the bearing brackets 20 supported on the base 18 is provided at its outer end with 65 a belt pulley 23 by which the shaft is driven and it has secured thereon between the bearings the worm 24 which meshes with the worm gear 25 secured on the outer end of the shaft 16. It will be noted that the three 70 supporting rolls 12 on one side of the tank are much higher than the similar supporting driving rolls 17 on the other side of the tank, and as a consequence a considerable portion of the weight of the tank rests on 75 the rolls 17 so that the rotation of the shaft 16 serves to rotate the tank by the friction of the rolls 17 with the rings 13.

The tank is composed of the inner cylindrical body portion 26 which has riveted 80 to the ends thereof the preferably concaved circular heads 27 and 28. Surrounding the inner shell or tank proper is the jacket which is made up of the cylindrical body portion 29 spaced apart from the body por- 85 tion 26 a suitable distance and having riveted to the ends thereof the preferably concaved circular heads 30 and 31. The rings 13 have the general contour of a railroad rail but with a very wide base 32, through 90 which base at suitable intervals are passed the supporting bolts 33 which pass through the shells 29 and 26 into which they are threaded and the rails 13 are secured in the desired position of adjustment by the lock 95 nuts 34 co-operating with the outer face of the bases 32 of the rails or rings 13.

In order in some cases to supply treating fluids to the contents of the tank and in other cases to draw off the fluid contents of 100 the tank, I locate in the tank a horizontal perforated pipe 35 which extends along the length of the tank near its bottom, when the tank is in the position shown in Fig. 3, and is secured from movement in the tank by 105 any suitable means, and the position of which is indicated on the exterior of the tank by some suitable indication, preferably by placing it in alignment with the external lug 36 to be subsequently described. 110

This pipe 35 is connected by an elbow 37 with the radially extending pipe 38 which is connected at its other end by the union 39 with an elbow 40 secured to a horizontal pipe 41 which is central of the tank and extends out through the stuffing boxes to be described and terminates, as shown in Fig. 6, in a stationary pipe 42 shown in Fig. 1 as connected by suitable short pipes 43 and 10 elbows 44 with a header pipe 45 to which is connected the five pipes 46, 47, 48, 49 and 50, each of which pipes is provided with a shut-off valve 46^a, 47^a, 48^a, 49^a and 50^a, and which pipes are conveniently connected respectively to a point for the discharge of waste gas; to a live steam supply; to a grease discharge tank; to a glue discharge tank; and to a hot water supply. Associated with the pipe 46 is a pressure gauge 46^b which serves to show 15 the pressure in the tank for the various purposes for which an accurate knowledge of the pressure is needed. Associated with the pipe 50 is a test cock 50^b from which a sample of the contents of the tank as they would 20 be delivered through the pipe 35, 41, etc., can at any time be taken. The pipe 42 terminates in a stuffing box 51 which has associated therewith the adjustable head 52 by which the stuffing, not shown, can be put 25 under the desired pressure. With the rotating pipe 41 passing through the stuffing box into the stationary pipe 42 it will be obvious that no leakage will occur in the passage of the fluids from the rotating pipe to 30 the stationary pipe.

At the same end of the tank I employ means for supplying steam or compressed air to the interior of the tank at its top or for exhausting the pressure at the top of 35 the tank, irrespective of the position to which it may be rotated, and for this purpose I have the pipe 53, provided with suitable perforations 54 in the upper end thereof extending from the highest position inside 40 the tank radially down to the center of the adjacent end of the tank, where the pipe 53 terminates in an annular enlargement or sort of a hub 55 which is screwed onto the threaded end of the stationary sleeve 56, best 45 seen in Fig. 4, which has its outer end closed by the cap 57 screwed therein. Associated with this cap 57 is a stuffing box 58, which may be of any desired construction, and which is employed to prevent leakage in 50 spite of the rotation of the tube 41 therein. The outer end of the sleeve 56 has threaded therein in suitable bosses a pipe 59 on the upper side which is connected to suitable means for supplying steam or compressed 55 air, as may be desired, and similarly secured in the under side is a pipe 60 which is connected with suitable means for exhausting the air or gases from the interior of the tank. The head 30 has bolted thereto the 60 stuffing box bearing 61 which rotates about

the exterior of the stationary sleeve 56, the stuffing box of course being employed to prevent leakage from the interior of the tank between the rotating bearing 61 and the stationary sleeve 56. The hub 55 of the 70 pipe 53 connects with the interior of the sleeve 56 through a plurality of apertures 62 in said sleeve, and consequently there is free communication through this stationary sleeve 56 either by the pipe 59 or 60, and the 75 pipe 53 to the top of the tank. To prevent leakage from the interior of the tank to the interior of the sleeve 56, I provide the stationary inner sleeve 63, which has its outer end entering a recess 64 in the cap 57 and engaging a gasket 65 in said recess. The inner end of the sleeve 63 is provided with a head 66 which is screwed into the internally threaded end of the sleeve 56, and which serves to hold the pipe 53 in place as well 80 as to close the end of the sleeve 56. The head 66 is provided in the flange 67 with the recesses 68 by which the necessary wrench can be applied to screw the sleeve 63 into place. At the same end of the tank, I preferably employ the circular, preferably concaved, shield 69 through the center of which the pipe 41 passes, and which terminates short of the central cylinder 26, to which it is secured at suitable intervals by the angular pieces 70 riveted at their ends to the shield and cylinder respectively. This shield 69 serves to keep the solid materials in the body of the tank from engagement 85 with the pipe 53 and the bearing at the center, and this promotes the durability of the apparatus. 90

Secured on the inner wall of the shell 26 are preferably provided suitable veins or blades 71 which serve to lift the material in 105 the tank as it rotates.

At the other end of the tank, I provide a short pipe 72, provided with suitable perforations, and passed by suitable liquid tight connections through the shells 28 and 31 into the boss 73 secured on the exterior of the head 31. This boss 73 has a passage therethrough and has the radially extending pipe 74 connected thereto and connected by the union 75 with a passage 76 in a small 110 head 77 secured to the center of the outside of the end 31. The pipe 74 is provided with cock 78 by which it can be opened or closed, as desired, and the associated pipe 72 is preferably located diametrically opposite in the 115 tank to the pipe 35, so that the position of the boss 73 or the boss 36 serves to show at any time the location of the pipes 72 and 35. On the other side of the head 77 is a passage 78 which is connected by the union 79 with 120 a pipe 80 which opens into the previously mentioned boss 36, which is secured to the end piece 31 and has an opening through said end piece so that the pipe 80 can thus be connected to the steam jacket surrounding 125 130

the tank proper. A cock 81 located in the pipe enables me to shut it off as may be desired, and I may here state that the purpose of this pipe is to free the jacket of the water 5 of condensation of the steam supplied thereto. The head 77 has projecting centrally therefrom the outer sleeve 82 and the inner sleeve or pipe 83, the two sleeves forming between them an elongated annular passage 10 84 connected to the passages 76 and 78. A head 85 is held in place by the pipes 86 and 87 screwed into suitable bosses formed in the top and bottom of the head and the outer side of the head is provided with the small 15 stuffing box 88 through which the sleeve 83 passes and in which it rotates. It will be noted that the sleeve 83 serves as a pipe leading from the steam jacket, and it will be understood that the outer end of this pipe 83 is 20 connected by a stuffing box such as is shown in Fig. 6 to a stationary pipe connected with a suitable supply of live steam for use in the steam jacket when desired. The head 85 has on the inner face of it, the body 89 of a 25 large stuffing box screwed into it, and this stationary stuffing box prevents the escape of fluids from the central cavity 90 of the head 85 through the space between the rotating sleeve 82 and its stationary bearing. To 30 close the end of the sleeve 82 and secure an adequate bearing against the end of the stuffing box 89, I screw into the internally threaded end of the sleeve 82 the nut 91, open at its center, and having the flange 92, 35 between which flange and the end of the stuffing box 89, I place the two flat bearing rings 93 and 94. The nut 92 is provided with suitable recesses 95 so that a wrench can be applied thereto. The pipe 87, previously mentioned, is employed to discharge 40 the water of condensation and is provided with a suitable connecting pipe 96 and a shut-off valve 97 which leads to any suitable discharge for the said water condensation. 45 The pipe 86 is connected to a suitable header pipe 98, to which is preferably connected the four pipes 99, 100, 101 and 102, each of said pipes being provided with an associated stop cock 99^a, 100^a, 101^a and 102^a, and the pipes 50 being for ordinary use preferably connected respectively with a hot water supply; a cold water supply; a steam supply; and a compressed air supply.

The use of my novel rendering tank will 55 be apparent to those skilled in the art. The employment of the steam jacket enables me to reduce materially the amount of time required in those steps which involve the evaporation of water and the drying of the residue, and the ability to draw off vapor by a 60 vacuum also contributes to this result. All ordinary rendering processes can be carried out by my tank rapidly and in a sanitary manner.

65 While I have shown and described my invention as embodied in the form which I at present consider best adapted to carry out its purpose, it will be understood that it is capable of modifications, and that I do not desire to be limited in the interpretation of 70 the following claims except as may be necessitated by the state of the prior art.

What I claim as new and desire to secure by Letters Patent of the United States is:

1. In an apparatus of the class described, 75 the combination with a central tank mounted to rotate on a horizontal axis, of a steam tight jacket surrounding and rotating with the tank but spaced therefrom, an eccentrically located pipe in the tank serving to 80 admit treating fluids thereto or to deliver finished fluids therefrom, means for supplying live steam to the jacket and removing the water of condensation therefrom by the pressure of the steam therein, and connections whereby said pipe can be operatively connected with any one of a plurality of stationary pipes despite the rotation of the tank. 85
2. In an apparatus of the class described, 90 the combination with a central tank mounted to rotate on a horizontal axis, of a steam tight jacket surrounding and rotating with the tank but spaced therefrom, an eccentrically located pipe in the tank serving to 95 admit treating fluids thereto or to deliver finished fluids therefrom, means for supplying live steam to the jacket and removing the water of condensation therefrom by the pressure of the steam therein, and connections whereby said pipe can be operatively connected with any one of a plurality of stationary pipes despite the rotation of the tank, said means including an axially located pipe opening into and rotating with 100 the jacket and in axial alignment with a stationary steam supply pipe, the two pipes being provided with an enclosing stuffing box at their junction. 105
3. In an apparatus of the class described, 110 the combination with a central tank mounted to rotate on a horizontal axis, of a steam tight jacket surrounding and rotating with the tank but spaced therefrom, an eccentrically located pipe in the tank serving to 115 admit treating fluids thereto or to deliver finished fluids therefrom, means for supplying live steam to the jacket and removing the water of condensation while the tank is rotating, connections whereby said pipe can 120 be operatively connected with any one of a plurality of stationary pipes despite the rotation of the tank, said means including an axially located pipe opening into and rotating with the jacket and in axial alignment with a stationary steam supply pipe, the two pipes being provided with an enclosing stuffing box at their junction, said means including a pipe connected to the periphery of the jacket at its outer end and at 125 130

its inner to a sleeve rotating with the tank, a stationary hollow bearing in which the end of the sleeve rotates, a stuffing box associated with the sleeve and bearing, and a stationary pipe opening into the hollow bearing.

4. In an apparatus of the class described, the combination with a central tank mounted to rotate on a horizontal axis, of a steam tight jacket surrounding and rotating with the tank but spaced therefrom, an eccentrically located pipe in the tank serving to admit treating fluids thereto or to deliver finished fluids therefrom, means for supplying live steam to the jacket and removing the water of condensation while the tank is rotating, connections whereby said pipe can be operatively connected with any one of a plurality of stationary pipes despite the rotation of the tank, said means including an axially located pipe opening into and rotating with the jacket and in axial alignment with a stationary steam supply pipe, the two pipes being provided with an enclosing stuffing box at their junction, said means including a pipe connected to the periphery of the jacket at its outer end and at its inner to a sleeve rotating with the tank, a stationary hollow bearing in which the end of the sleeve rotates, a stuffing box associated with the sleeve and bearing, a stationary pipe opening into the hollow bearing, said means including an axially located pipe opening into and rotating with the jacket in axial alignment with a stationary steam supply pipe, a stuffing box enclosing the two pipes at their junction, a sleeve surrounding the axially located pipe between the jacket and the stuffing box, a stationary hollow bearing in which the outer end of the sleeve rotates, a stuffing box associated with the sleeve and bearing, a stationary pipe opening into the hollow bearing, and a radially extending pipe connected to the periphery of the jacket at its outer end and at its inner end to the interior of said sleeve.

5. In an apparatus of the class described, the combination with a central tank mounted to rotate on a horizontal axis, of a steam tight jacket surrounding and rotating with the tank but spaced therefrom, a stationary pipe open at its upper end within the tank and extending radially from a point near the top of the tank to its axis at one end, means for supplying live steam to the jacket and removing the water of condensation therefrom by the pressure of the steam therein, and connections whereby said pipe can be operatively connected with any one of a plurality of stationary pipes despite the rotation of the tank.

6. In an apparatus of the class described, the combination with a central tank mounted to rotate on a horizontal axis, of a steam

tight jacket surrounding and rotating with the tank but spaced therefrom, a stationary pipe open at its upper end within the tank and extending radially from a point near the top of the tank to its axis at one end, means for supplying live steam to the jacket and removing the water of condensation therefrom by the pressure of the steam therein, connections whereby said pipe can be operatively connected with any one of a plurality of stationary pipes despite the rotation of the tank, said connections including a stationary sleeve into which the inner end of the pipe opens extending axially through the adjacent end of the tank and jacket, and a stuffing box connected to the end of the tank and surrounding the sleeve.

7. In an apparatus of the class described, the combination with a central tank mounted to rotate on a horizontal axis, of a steam tight jacket surrounding and rotating with the tank but spaced therefrom, an eccentrically located pipe in the tank rotating therewith and serving to admit treating fluids thereto or to deliver finished fluids therefrom, a stationary pipe opening at its upper end within the tank and extending radially from a point near the top of the tank to its axis at one end, means for supplying live steam to the jacket and removing the water of condensation while the tank is rotating, a radial pipe connected to the eccentric pipe at one end, an axial pipe to which said radial pipe is connected at the other end extending through the end of the tank and jacket, a sleeve surrounding the axial pipe and held from rotation, and into the inner of which the stationary pipe opens, a stuffing box cap closing the outer end of the sleeve, the stuffing box surrounding the rotating axial pipe and co-operating with the cap, and a second smaller sleeve surrounding the axial pipe and closing and extending from the inner end of the first sleeve to the stuffing box cap in which it is seated.

8. In an apparatus of the class described, the combination with a central tank mounted to rotate on a horizontal axis, of a steam tight jacket surrounding and rotating with the tank but spaced therefrom, an eccentrically located pipe in the tank serving to admit treating fluids thereto or to deliver finished fluids therefrom, means for supplying live steam to the jacket, connections whereby said pipe can be operatively connected with any one of a plurality of stationary pipes outside the tank despite its rotation, an eccentrically located pipe tank diametrically opposed to the first eccentrically located pipe and passing to the exterior of the tank through the jacket, a radially extending pipe outside the tank connected to the second eccentric pipe at its outer end, a valve in said radially extending pipe, a second radially extending pipe out-

side the tank opening at its inner end into the jacket, a valve in said second radially extending pipe, a common sleeve secured axially to the end of the tank into which 5 both radially extending pipes open, a hollow stationary bearing in which the sleeve rotates, and a pipe connected to the hollow of the bearing.

9. In a device of the class described, the 10 combination with a cylindrical tank having a horizontal axis, of a series of plain annular rails surrounding the same, two aligned series of plain rollers co-operating with said rails, the line of one series being 15 located at a higher elevation than the line of the other series so that the weight of the tank will be more largely thrown upon the lower series, a shaft upon which said lower series of rollers are secured, and means for 20 rotating said shaft.

10. In a device of the class described, the 25 combination with a cylindrical tank having a horizontal axis, of a series of annular rails surrounding the same, two series of rollers co-operating with said rails, one series being 30 located above the other series so that the weight of the tank will be more largely thrown upon the lower series, a shaft upon which said lower series of rollers are secured, a worm gear on the shaft, a trans-

verse shaft, driving means therefor, and a worm secured thereon meshing with the worm gear.

11. In a device of the class described, the 35 combination with a cylindrical tank having a horizontal axis, of a series of annular rails surrounding the same, two series of rollers co-operating with said rails, axial connections with the interior of the tank through the ends thereof, and means for adjusting 40 the rails on the tank.

12. In an apparatus of the class described, the combination with a tank mounted to rotate on a horizontal axis, of an eccentrically-located pipe in the tank serving to admit 45 treating fluids thereto or to deliver finished fluids therefrom, a stationary pipe within the tank extending at one end from the axis to the periphery and having external connections through the bearing on which the 50 tank rotates, and a circular shield carried by the tank and located between the radial portions of two pipes to protect the stationary pipe from solids.

In witness whereof, I have hereunto set 55 my hand and affixed my seal, this 24th day of June, A. D. 1918.

WILLIAM LISTER. [L. S.]

Witness:

JOHN HOWARD McELROY.
